United States Patent

Des. 240,667
Patented July 20, 1976

240,667

SAUNA

Joseph G. Hall, 102 Geary Ave.,
Kentfield, Calif. 94904

Filed May 6, 1974, Ser. No. 466,959

Term of patent 14 years

Int. Cl. D24—99; D25—02
U.S. Cl. D83—1 C

FIG-1

FIG-2

FIG-3

FIG. 4

FIG. 5

FIG. 1 is a perspective view of a sauna embodying my new design.

FIG. 2 is a top plan view of the sauna shown in FIG. 1.

FIG. 3 is a front elevational view of the sauna shown in FIG. 1.

FIG. 4 is a right side elevational view of the sauna of FIG. 1.

FIG. 5 is a side elevational view of the sauna of FIG. 1 taken along line 5—5 in FIG. 2.

I claim:

The ornamental design for a sauna, as shown.
